US0D1028311S

(12) **United States Design Patent** (10) **Patent No.:** **US D1,028,311 S**
(45) **Date of Patent:** **** May 21, 2024**

(54) **LIGHTING DEVICE**

(71) Applicant: **Nite Ize, Inc.**, Boulder, CO (US)

(72) Inventor: **Leo Lesperance**, Lafayette, CO (US)

(73) Assignee: **NITE IZE, INC.**, Boulder, CO (US)

(**) Term: **15 Years**

(21) Appl. No.: **29/876,968**

(22) Filed: **May 31, 2023**

(51) **LOC (14) Cl.** **26-02**

(52) **U.S. Cl.**

USPC **D26/37**

(57) **CLAIM**

The ornamental design for a lighting device, as shown and described.

DESCRIPTION

FIG. 1 is a front perspective view of a lighting device showing the new design;

FIG. 2 is a rear perspective thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

1 Claim, 8 Drawing Sheets
